UNITED STATES PATENT OFFICE

155,100

DESIGN FOR A TIE RACK

Harry L. Millward, Sr., Steelton, Pa.

Application March 8, 1948, Serial No. 144,969

Term of patent 7 years

(Cl. D33—8)

To all whom it may concern:

Be it known that I, Harry L. Millward, Sr., a citizen of the United States, residing at Steelton, in the county of Dauphin and State of Pennsylvania, have invented a new, original, and ornamental Design for a Tie Rack, of which the following is a specification, reference being had to the accompanying drawing, forming part thereof.

Figure 1 is a front elevational view of a tie rack, showing my new design, and

Figure 2 is a side perspective view thereof.

I claim:

The ornamental design for a tie rack, as shown.

HARRY L. MILLWARD, SR.
